UNITED STATES PATENT OFFICE

2,328,944

TRANSMISSION SYSTEM EMPLOYING
PULSE MODULATION

William Arnold Beatty, Sidcup, England, assignor
to International Standard Electric Corpora-
tion, New York, N. Y.

Application May 8, 1940, Serial No. 333,945
In Great Britain May 30, 1939

7 Claims.

(Cl. 250—9)

This invention relates to radio transmission systems utilising pulse modulation in a plurality of channels, and resides in a system wherein the fixed edges of the basic time-modulated pulses for the different channels are synchronised. The invention is applicable to two-way communication systems and to systems employing a number of transmitter-receivers, as well as to transmitters single or multiple operating simultaneously on different wavelengths.

In copending United States Patent No. 2,256,336, issued September 16, 1941, for Pulse modulation system and application Ser. No. 312,645, filed January 6, 1940 for Electric signalling systems, there are described methods of generating pulses which are suitable for pulse modulation. The former describes methods of generating pulses coded as S/RT and S/RL, while the latter describes methods of generating pulses coded as RT+S/RT and RL+S/RL.

Throughout the following description

RT+S/RT

pulses will be considered as also including RL+S/RL pulses, as both types are similar in essential characteristics.

In an RT+S/RT pulse system the RT portion of the pulse, in addition to supplying intelligence to amplitude modulated receivers, also supplies timing for the insertion of pulses corresponding to the trailing edges of the combined RT+S/RT pulses, these trailing edges occurring at equal time intervals.

The present invention deals especially with methods of utilising one timing pulse train for more than one transmission system having S/RT pulses. The timing pulse train may be time modulated in accordance with intelligence or may be time modulated and combined with an S/RT pulse giving an RT+S/RT pulse, or the timing pulse may be unmodulated as regards time.

Various aspects of the invention are set out in the appended claims.

The accompanying drawing serves to illustrate certain features of the proposal. In the drawing:

Fig. 1 shows a rectangular pulse utilised for synchronising transmitters and receivers;

Fig. 2 shows three target plate arrangements for pulse generators;

Fig. 2A is a partial diagrammatic view illustrating a modified arrangement to be used in connection with the target plate arrangement shown in Fig. 2; and

Fig. 3 shows in block schematic form four pulse transmitters.

Referring to Fig. 1, there is shown a train of rectangular pulses 21 occurring at equal time intervals having a duration of 5% of the interval between consecutive pulses. The frequency of occurrence can be, for example, 20,000 per second. The leading edges 22 of the pulses 21 are used to synchronise a saw-tooth wave-form generator which is used for the deflection of an electron beam of an S/RT type pulse generator 23 Fig. 2, as described and shown in Figs. 1, 2, 3 and 11 of Patent No. 2,256,336. The pulse 21 is also used to suppress the electron beam during the flyback stroke, as described in the above mentioned Patent No. 2,256,336.

Referring to Fig. 2 of the present invention, there are shown two other pulse-generator collector plate arrangements 24 and 25, which are similar to the arrangement 23. The saw-tooth wave-form used for deflecting the beam across the target 23 can also be used to deflect independent electron beams across each of the targets 24 and 25, or alternatively the pulses 21 can be made to synchronise independent saw-tooth generators for each pulse generator. The beams in the various pulse generators are independently deflected in directions at right angles to the deflection due to the saw-tooth wave-form by signals corresponding to three independent kinds of intelligence, for instance, three telephone messages, thereby generating three independent groups of S/RT pulses which are characteristic of three different kinds of intelligence.

The pulse 21 in addition to synchronizing the generation of the various groups of S/RT pulses is utilised to modulate a transmitter 26 Fig. 3, which, for example, can radiate on a wavelength of 8 metres. The S/RT pulses derived from the plates 23, 24 and 25 can be utilised to modulate the transmitters 27, 28 and 29 respectively which, for example, can radiate on 1.75, 2 and 2.5 metres respectively.

At a receiving location remote from the transmitters 26, 27, 28 and 29, a receiver (not shown) capable of receiving the transmission on 8 and 1.75 metres is provided. The leading edges 22 of the pulses 21 on the 8 metre transmission are utilised to give the fixed edge pulses of a double pulse modulation system, while the S/RT pulses of the 1.75 metre transmission supply the variable edge pulses of the same double pulse modulation system. In any known manner the variable edge pulses and the fixed edge pulses can now be utilised to supply intelligence corres-

sponding to the original intelligence used for vertically modulating the electron beam which is being deflected across the target 23.

Should two-way communication be required between the transmitter and receiver points, the signal received from the 8 metre transmitter 26 can also be utilised to synchronise another S/RT pulse generator at the receiving station, and these S/RT pulses can modulate another short wave transmitter working for instance on 1.9 metres. This latter transmission can now be received at the original transmitting location and as already described the S/RT pulse modulation can be utilised to give intelligence similar to that causing the generation of the S/RT pulses at the remote location.

In a similar manner the transmissions radiated by the transmitters 28 and 29 can be received at other locations, and if desired, two-way communication can also be established between these points and the original transmitting station.

It should be obvious from the foregoing that it is not essential for the transmitter 26 to be located in the same place as the transmitters 27, 28 and 29, and that two-way communication can be established between any two locations, provided the generation of the S/RT pulses is made dependent upon the time of occurrence of the pulses 21.

One reason for keeping the pulses 21 of a relatively short duration is that these pulses can be utilised to give electron beam suppression during the flyback strokes of the saw-tooth waveform signals used for deflecting the beam in the various pulse generators, and provided that in the case under consideration the flyback is less than 5% of the total waveform duration, it would be a disadvantage to make the pulse 21 any longer in its duration, as then portions of the forward stroke of the saw-tooth signals would be unnecessarily suppressed with the result that the intervals between pulses would be made unnecessarily large.

In cases where it is not desired to establish two-way communication it is not necessary for the pulse radiated by the transmitter 26 to be of short duration, the only essentials being that the pulses have the same frequency of occurrence as the pulses 21 and have one edge occurring at equal time intervals. The pulses radiated from the transmitter 26 can be time modulated in accordance with intelligence and can, for instance, be RT or RL pulses as described in the above mentioned Patent No. 2,256,336, or can be RT+S/RT or RL+S/RL pulses as described in Application Ser. No. 312,645. Such an alternative arrangement has been diagrammatically indicated in Fig. 2A, showing a source of pulses of variable duration connected to the saw tooth wave generator in place of the source of pulses having one edge occurring at equal time intervals, as illustrated in Fig. 2.

Although the foregoing description relates to the generation of S/RT pulses, it is obvious that it can be applied to any pulse generating system in which linear deflection of an electron beam across a target plate or other collector is utilised for the purpose of generating time modulated pulses.

In British Patent No. 527,904 dated October 18, 1940 there are described methods of synchronising a pulse modulated sound transmission of an accompanying vision signal by means of the synchronising pulses of an accompanying television transmission. It should now be obvious that

the synchronising pulses of a vision transmission can be utilised in such a manner that they synchronise a plurality of pulse generators for the purposes described in the foregoing proposal.

It will be appreciated that a large measure of secrecy can be attained by the invention, since detection can be made dependent upon the reception of two-pulse trains of different and not necessarily constant carrier frequency, the pulse trains being unintelligible without information as to their manner of use.

Although in the foregoing it has been proposed to synchronise the pulse trains of the different channels by the transmission of a marking pulse, synchronisation may in some cases be effected directly between adjacent transmitters and in other cases other methods become possible. Synchronising signals may be sent by wire at their natural frequency or as a modulation.

What is claimed is:

1. A radio transmission system comprising at least one transmitter adapted to transmit variable edge pulses characteristic of a sound or like wave, and another transmitter adapted to transmit complementary fixed-edge pulses and means at a receiving point for combining the effects of the impulses from said transmitters in order to derive therefrom intelligence transmitted by one of said transmitters.

2. A radio transmission system employing pulse modulation for transmission of telephonic signals or the like, comprising means for producing a series of spaced impulses for synchronizing purposes, a plurality of transmitters adapted to transmit pulse modulated signals, means for synchronizing said transmitters with said spaced synchronizing impulses, whereby a component of each pulse modulated signal from the respective transmitters has a time relation fixed in respect to said impulses, and means for transmitting said spaced synchronizing impulses for use in demodulating signals from all of said transmitters.

3. A radio transmission system according to claim 2 wherein said spaced synchronizing impulses have equal durations of the order of 5% of the interval between consecutive ones of such impulses.

4. A radio transmission system according to claim 2 wherein said means for transmitting said spaced synchronizing impulses are adapted to transmit a train of impulses having one edge spaced at constant time intervals for synchronizing purposes, and further comprising means for varying the duration of said spaced synchronizing impulses in accordance with a further signal to be transmitted.

5. A secret radio transmission system for simultaneous transmission of a plurality of telephonic signals or the like comprising a plurality of sources of signals, a common source of synchronizing pulses, a plurality of pulse modulation means for producing under the control of each one of said sources a corresponding series of brief pulses whose time position in respect to that of the synchronizing pulses from said source represents the momentary amplitude of the corresponding signal, means for transmitting all of said series of pulses on different carrier wave lengths, means for synchronizing said plurality of pulse modulating means, whereby the time positions of the pulses of the respective wave lengths are all related to the same standard of time position, and means for transmitting a single series of synchronizing pulses for use in the demodulation of all of said first mentioned pulses.

6. A radio transmission system according to claim 5 wherein one of said modulating means is located at a first station and another of said modulating means is located at a second station, and wherein said means for synchronizing said pulse modulating means comprises means for transmitting radio signals from said first station to said second station.

7. A radio receiver of the system according to

claim 2, comprising means for receiving said pulse modulated signals, means for receiving said spaced synchronizing impulses, and means for demodulating said pulse modulated signals and said spaced synchronizing impulses in accordance with the time relation between said spaced synchronizing impulses and said modulated signals.
